(57) **CLAIM**

We claim the ornamental design for an speaker unit, as shown and described.

DESCRIPTION

FIG. 1 is a front perspective view of a speaker unit in accordance with the present design;

FIG. 2 is a rear perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof;

FIG. 8 is a left side view thereof;

FIG. 9 is a front view thereof with the speaker cover removed;

FIG. 10 is a rear view for the speaker cover of the speaker unit; and,

FIG. 11 is a front view of an alternate embodiment of FIG. 1 with the speaker cover shown in a textile pattern.

The broken line showing on the drawing disclosure is for illustrative purposes only and forms no part of the claimed design.
